(74) **Attorney, Agent, or Firm:** Quarles & Brady LLP

(57) **CLAIM**

The ornamental design for a camera, as shown and described.

DESCRIPTION

FIG. 1 is a perspective view of a camera in a first position in accordance with the new design;

FIG. 2 is a front view of the camera of FIG. 1;

FIG. 3 is a back view of the camera of FIG. 1;

FIG. 4 is a right side view of the camera of FIG. 1;

FIG. 5 is a left side view of the camera of FIG. 1;

FIG. 6 is a top view of the camera of FIG. 1;

FIG. 7 is a bottom view of the camera of FIG. 1;

FIG. 8 is a front view of the camera of FIG. 1 rotated into a second position; and,

FIG. 9 is a perspective view of the camera of FIG. 1 rotated into the second position.

The broken lines depict portions of the camera and form no part of the claimed design.

1 Claim, 8 Drawing Sheets
